(57) **CLAIM**

The ornamental design for a chromatograph cabinet, as shown and described.

DESCRIPTION

FIG. 1 is a front, left perspective view of a chromatograph cabinet showing our new design therefor;

FIG. 2 is a front view thereof;

FIG. 3 is a top view thereof;

FIG. 4 is a rear view thereof;

FIG. 5 is a right side view thereof; and,

FIG. 6 is a left side view thereof.

The dash-dash broken lines in the figures and the lower opacity areas within the dash-dash lines show portions of the chromatograph cabinet that form no part of the claimed design.
